UNITED STATES PATENT OFFICE.

WILLIAM M. TISDELL AND LUDWIG S. PULS, OF LOS ANGELES, CALIFORNIA.

GARMENT SLEEVE WITH DETACHABLE AND REVERSIBLE CUFF.

Application filed April 8, 1922. Serial No. 550,784.

This invention relates to a detachable and reversible cuff for the sleeves of garments, and its principal objects are, to provide

5 First. A detachable cuff for the ordinary soft shirt usually worn by men, though the invention may be applicable to garments of any kind upon which cuffs are used.

10 Second. A detachable cuff which shall have the same appearance, while being worn, as the ordinary cuff which is integral with the sleeve of the garment.

15 Third. A detachable cuff which shall be reversible, thus enabling the wearer to economize in the expense for laundering, by having several distinct cuff surfaces adapted for service.

20 Fourth. A detachable and reversible cuff adapted to present a clean surface both on the outside and inside thereof, each time the cuff is turned.

Fifth. A detachable, reversible cuff, which may be easily and quickly manipulated.

Sixth. A cuff which shall be economical to manufacture and which shall at the same 25 time, have good wearing qualities and a faultless appearance.

In attaining these objects, we provide each sleeve of the shirt or other garment with a wrist band, which may be of considerable 30 width in the direction of the length of the sleeve. The sleeve may be placketed, and the wrist band may be provided with a buttonhole near each of its extremities as usual. The cuff, in its developed or opened-out 35 form, is made preferably in the shape of a rectangular envelope closed along three edges while the fourth or top edge is left open. For convenience, the term "envelope" will hereinafter be used in referring to the 40 cuff in its developed or opened-out form.

The wrist band of the sleeve is adapted for insertion into this envelope through the open edge of the latter and the dimension of the envelope in the direction of the length of the sleeve, or from the open edge to the 45 opposite closed edge of the envelope, is about twice the width of the finished cuff in the direction of the sleeve length.

The envelope is adapted for folding back 50 upon itself so as to bring the lower or closed edge adjacent, and into alignment with, the open edge. Four buttonholes may be provided in the envelope, and be so located that one pair of buttonholes shall register with 55 the buttonholes in the wrist band when the latter is inserted through the open edge, and

further, so that the second pair of buttonholes shall come into registry with the first mentioned buttonholes when the cuff is folded over upon itself as above explained. 60

Both exterior surfaces of the envelope are intended to present two alternate exterior cuff surfaces to view, either one of the exterior faces of the envelope being adapted to form, upon the first folding back of the envelope, an exterior cuff surface exposed to general outside view and an inner cuff surface which comes next the wrist of the wearer. Upon the second folding back of the envelope, that is, in the opposite direction, the previously exposed surfaces which in the meantime have become soiled, may be folded in, entirely out of sight, and two entirely fresh surfaces be exposed, one surface to the general outside view and the 70 other next the wrist of the wearer as before.

If desired, the envelope may be so made that it can be turned inside out. By having the envelope lined with the same kind of cloth as is used for the outside thereof, or if the envelope is made of a double-faced cloth, the turning inside out of the envelope again presents two completely fresh exterior wearing surfaces which may be brought into use in exactly the same manner as has 80 already been described for the first two surfaces.

In other words, each envelope may have from two to four entirely fresh wearing surfaces, each surface upon becoming soiled, 90 being turned inwardly, completely hidden from view, with fresh, clean cuff surfaces exposed to the outside.

While we are aware that detachable cuffs have hitherto been made for one purpose or another, and also, that reversible cuffs are not broadly new, yet it has not come to our knowledge that our method of achieving the desired end has ever been in use before. 95

The features which we believe to be new, and for which the protection of Letters Patent is desired, are collectively grouped in the claims, forming the conclusion of this specification. 100

In the drawing,

Fig. 1 represents an elevation of the lower part of a garment sleeve and cuff embodying our invention and showing same ready to be worn.

Fig. 2, a perspective view, showing the 110 cuff in the detached position ready to receive the wristband of the garment sleeve.

Fig. 3, an elevation of sleeve and cuff envelope before the latter is folded into final wearing position.

Fig. 4, a section taken on line 4—4, Fig. 3.

Fig. 5, an elevation of the sleeve wristband.

Fig. 6, a section, enlarged, taken on line 6—6, Fig. 1.

Fig. 7, a section, taken on line 7—7, Fig. 3.

Throughout the different views, similar parts are designated by similar reference characters.

Referring to the drawing, numeral 26 indicates the representation of part of a shirt sleeve made of a striped material, while 10 illustrates the cuff in the form of a plain envelope having the three closed edges 12, 14 and 15, and the open upper edge 16, Figs. 2, 4 and 6. Buttonholes 17 are worked 20 separately in each of the walls 21 and 24 of the envelope as indicated in Fig. 7. Buttonholes 18 are similarly worked, as may also be buttonholes 19 and 20. The wristband 25 of the sleeve 26 may be inserted in the 25 upper part of the envelope and the cuff link be passed through the buttonholes 18 of the envelope and through the buttonhole 27 of the wristband 25 as shown in Figs. 3 and 4. In order to finish the attaching of the cuff 30 from this position, the envelope may be folded upwardly around the line 29—29 (Fig. 3) as an axis. The folding may be in the direction of either the arrow 42 or the arrow 43 (Fig. 4), depending upon 35 which surface of the cuff is to be exposed to the outside. The buttonholes 19 thus come into registry with the buttonholes 18 and may be fastened by the cuff link 30. The opposite buttonhole edge of the cuff may 40 then be brought around in the same manner as an ordinary cuff and the link be passed through the buttonholes 17, 28 and 20, thus completing the fastening of the cuff and leaving same ready to be worn, as shown 45 in Fig. 1.

The wristband 25 is preferably made of considerably greater width at or near the center 31 than at the edges 32 and 34, the purpose of this being to afford a greater frictional surface between the inside of the cuff and the wristband. If found desirable, an extra piece 60 (Fig. 5) of coarse cloth forming a light pad, may be sewed to the outside of the wristband in order to provide a still greater frictional contact. This frictional contact between the inside surface of the cuff and the outside surface of the wristband is largely depended upon to hold the cuff in place as indicated at 55, Fig. 1.

The envelope may be made in either of the two different ways previously mentioned. These two ways may be designated as (a) and (b) and both may be described with 60 reference to Fig. 2. In (a) the two outside

surfaces of the walls 21 and 24 would show the right side of the envelope material while the inside of the envelope might be lined with a different material. Therefore, there would be two surfaces available for wear as illustrated in Figs. 3 and 4, the two usable outside surfaces being indicated at 40 and 41, Fig. 4. When the envelope is folded up in the direction of the arrow 42, the portions 41 and 47 thereof, will form the exposed cuff surfaces, while if the envelope is folded in the direction of the arrow 43, the portions 40 and 48 thereof, will form the exposed cuff surfaces; thus each outside envelope surface furnishes an 80 inside cuff surface and an outside cuff surface.

The cuff is attached to the wristband solely by an ordinary cuff link, there being no other fastening. The wristband when properly 85 made, furnishes enough friction throughout its surface, and especially near the point 31 (Figs. 3 and 5) which is located approximately opposite the placket of the sleeve when the latter is brought around into the finished wearing position, to hold the cuff securely in place, as indicated in Figs. 3 and 6.

Ordinarily, the most desirable way of 90 wearing our cuff is as illustrated in Fig. 6, where one wall of the cuff envelope is shown on the inside of the wristband, while three wall thicknesses are shown on the outside thereof. However, if desired, the single 95 wall could be placed on the outside and the three walls placed on the inside according to 100 the choice of the wearer.

While for convenience a specific embodiment of this invention is herein shown and described, it should be clearly understood 105 that the detailed parts thereof may, or may not, appear in the preferred forms, and further, that the preferred forms may vary from time to time as the developement of this invention and the arts with which it is 110 identified, progress.

Having fully described our invention, what we claim is:—

1. The combination with a sleeve portion having a wristband attached thereto, of a detachable cuff having three closed edges and one open edge adapted to receive said wristband along the open edge thereof, the said cuff being adapted to fold upwardly in an inward or outward direction, and a plurality of button-holed portions suitably disposed in said wristband and in the said cuff, all of the said button-holed portions being adapted to register with each other when the said cuff is folded up and brought around into the wearing position.

2. The combination of a reversible envelope having two walls adapted to form a cuff, the said envelope being open along one edge thereof and closed along the remaining

edges, and a sleeve portion having a wristband projecting into the said envelope along the open edge, the said envelope being arranged for alternately folding upwardly in 5 each of two directions, and after folding, to be brought around into the wearing position and a plurality of buttonholed portions so disposed in said wristband and in each of the two walls of the said envelope that all 10 of the said buttonholed portions shall register with each other when the cuff is brought into the wearing position.

3. The combination of an envelope adapted to form a cuff, said envelope having two walls 15 joined to each other along three edges thereof, and having an open edge for turning inside out, and a sleeve portion having a wristband arranged for fitting into the said en-

velope through the open edge and between the walls thereof in either the normal or the 20 inside-out form, and means for fastening the said cuff to the said sleeve portion.

4. A detachable and reversible cuff comprising an envelope formed of suitable material and foldable along a longitudinal 25 median line, said envelope being open along one longitudinal edge to receive a sleeve cuff between the two sides thereof, each of such sides having two pairs of independent button holes formed therein and arranged to 30 register with each other when the cuff is folded.

In testimony whereof, we sign our names hereto:

WILLIAM M. TISDELL.
LUDWIG S. PULS.
